UNITED STATES PATENT OFFICE.

MERRILL H. HATHAWAY, OF SPRINGFIELD, MASSACHUSETTS.

BRUSH-HOLDER FOR DYNAMOS AND MOTORS.

SPECIFICATION forming part of Letters Patent No. 478,104, dated July 5, 1892.

Application filed October 8, 1891. Serial No. 408,117. (No model.)

To all whom it may concern:

Be it known that I, MERRILL H. HATHAWAY, of Springfield, in the county of Hampden and State of Massachusetts, have invented a new and useful Improvement in Brush-Holders for Dynamos and Motors, of which the following is a specification, reference being had to the accompanying drawings, forming part thereof.

10 My invention relates to holders for the contact-brushes of dynamos and electric motors, and has for its object to provide a holder which, while simple and inexpensive in construction, will have improved means for holding and advancing the brush to compensate for wear of the latter and which can be readily applied to any of the various forms of dynamos and motors.

To this end my invention consists in the 20 brush-holder constructed and operating as hereinafter fully described, and particularly pointed out in the claims.

Referring to the drawings, in which like letters designate like parts in the several figures, Figure 1 is a view in perspective of the commutator of a dynamo or electric motor having applied thereto a brush-holder embodying my invention. Fig. 2 is a longitudinal section of the holder, taken upon line 2 2 25 of Fig. 3. Fig. 3 is a cross-section taken upon line 3 3 of Fig. 2. Fig. 4 is a detached view of the follower.

The letter *a* designates the rectangular body of the holder, which has its front end, or that 35 end next to the commutator, open and is provided with a removable bottom *a'*, preferably sliding in ways in the two side pieces *a*², as shown in Fig. 3. The rear end *a*³ of the holder is made integral with or is rigidly se- 40 cured to said bottom and is provided at its center with an outwardly-projecting hub *a*⁴, which serves as a guide for the notched or toothed stem by which the follower is ad- 45 vanced, which stem passes therethrough. Within said body is located the follower *b*, whose area is substantially that of the cross- 50 sectional area of the interior of the body, as shown in Fig. 3, whereby it is adapted to have a free sliding movement within the body 55 without possibility of binding at any point. Said follower is preferably provided at each end thereof with the rearwardly-projecting

wings *b'*, which assist in steadyng its move- 60 ment within the body, and is provided at its center with the rearwardly-projecting hub *b*², 55 which is preferably tubular in form, as shown, and which forms a socket to receive the coil- 65 spring *c*. Said spring *c* is preferably secured at its rear end to the notched or toothed stem *d* and at its front end bears against the fol- 70 lower, whereby it is caused to exert a con- 75 stant pressure upon the latter toward the front end of the holder, the socket *b*² prevent- 80 ing any material lateral deflection thereof. The stem *d* has its notches or teeth inclined 85 rearwardly and is provided at its rear end with a suitable head *d'* to enable it to be 90 conveniently manipulated. I have herein shown said stem as consisting of a round rod and the hub *a*⁴ at the rear end of the body as being tubular in form to form a 95 guide therefor; but it will be understood that said stem and guide can be made of rect- 100 angular or other angular form in cross-section, if desired. I have also shown herein a tube *a*⁵ secured to the front side of the end piece *a*³ and forming a continuation of the tubular guide *a*⁴ to assist in truly guiding the stem and the spring, said tube at its front end having a telescopic action within the hub *b*² on the follower; but in practice said hub *b*² can itself be somewhat elongated and the intermediate tube *a*⁵ omitted, if desired. In connection with said follower, spring, and notched or toothed stem I employ a spring-actuated 105 detent to engage the notches or teeth on the stem in such manner as to prevent rearward movement of the latter, while permitting a free forward movement thereof. Various forms of detents for such purpose can be utilized; but I have shown and prefer to use one 110 which is capable of performing the additional function of locking the removable bottom and rear end piece in position upon the body of the holder. Said detent (designated by the letter *e*) is pivoted between two ears *a*⁶, pro- 115 jecting from the upper side of the body *a* near its rear end, and has its long arm extending toward the front end of the body and termin- 120 ating in a suitable finger-piece, as shown, and has its short arm curved downwardly and terminat- 125 ing at its extreme end in a bearing- 130 face *e'*, adapted to engage the outer end of hub *a*⁴, and a beveled and transversely-curved

point e^2 , (see broken lines in Fig. 3,) adapted to engage the notches or teeth on the stem. A coil-spring e^3 , bearing against the under side of said detent at its front end, serves to normally retain its rear end in engagement with said hub and the stem. The bearing-face e' is of such width as to permit the detent to ride over the teeth on the stem as the latter is pushed inwardly without disengaging said face from the hub a^4 .

It will be observed by reference to Fig. 2 that the follower is adapted to be advanced to the extreme front end of the body a , and to avoid the possibility of its being projected entirely out of the body and lost I prefer to provide means for checking its movement at said extreme front end of the latter, and as one example of such means I have shown said follower as having projecting laterally from the wings b' thereof a stud or pin b^3 , which studs enter grooves a^7 in the inner surface of the side pieces a^2 of the body, said grooves extending from the rear end of said side pieces to a point just short of their front end, as shown by full and broken lines in Fig. 2.

The carbon or other brush f is inserted within the front end of the body with its rear end against the follower and its front end projecting to the desired distance beyond the body, and when so inserted is securely held against all movement except one toward the front end of the holder in a plane parallel with the side pieces a^2 of the latter. Its front end is therefore presented squarely to the periphery of the commutator g at all times and under all circumstances. The spring c presses the brush against the commutator with a pressure which is constant and which is kept substantially uniform as the face of the brush wears away by pushing the stem d inwardly one or more notches at a time, as may seem necessary, the detent rigidly holding said stem in its adjusted position. It will be seen that such movement of said stem to compensate for wear of the brush can be performed instantly and by the sense of touch alone, in which respect my device differs materially from such holders as employ a threaded stem and a check-nut or other device for locking it against rotation. This feature of the holder devised by me is especially valuable and important when the holder is applied to motors for propelling street-cars and used in other similar situations where access to the holders is obtained with difficulty. The seating of the brush within the holder is such that it will be held properly to its work and can be used until almost entirely worn away, even though it be cracked or broken, and the usual frequent renewal of the brushes is therefore obviated. It will be observed, also, that there are no exterior springs or other parts liable to be broken and thrown against the commutator to form a short circuit, as now frequently happens, all of the parts except the detent and its spring, which can have no breaking-strain exerted upon them, being completely

housed within the body. The removable bottom and the parts mounted thereon can be readily withdrawn from the body without disturbing the connection of the latter with the dynamo or motor by simply depressing the front end of the detent and can be as readily replaced in the body.

I have shown the holder as being secured to a bracket-arm g' of a dynamo or motor by means of a threaded bolt projecting laterally from the holder through said arm and receiving a lock-nut at its outer end; but it will be obvious that the holder, constructed as herein described is adapted to be applied to any of the various forms of dynamos and motors in use and by any of the fastening means heretofore employed. The holder herein described, moreover, is strong and durable in all of its parts, while being of simple and comparatively inexpensive construction.

It will be understood that, while I have herein described the holder as being provided with a removable "bottom," that term is used with reference to the position in which the holder is illustrated in the drawings, and that should the holder be used in a reverse position to that shown said removable bottom would become a removable cover, it being wholly immaterial to the perfect operation of the holder as described whether it be used in the one or the other position, the rear end piece in either case being formed integral with or rigidly secured to the removable part.

As hereinbefore stated, while I have shown a single detent-lever for engaging the notched or toothed bar and also retaining the removable bottom and end piece upon the body, it is entirely obvious that two separate detents for such purpose can be employed within the scope of my invention, if desired.

Having thus fully described my invention, what I claim, and desire to secure by Letters Patent, is—

1. The brush-holder for dynamos and motors herein described, comprising, in combination, a holder-body adapted to receive a carbon or other brush, a follower suitably guided within said body and adapted to bear against the rear end of said brush, a notched or toothed stem guided at the rear end of said body for longitudinal movement, a spring-actuated detent engaging the notches or teeth on said stem and adapted to hold the same against rearward movement, and a spring interposed between the front end of said stem and said follower, substantially as described.

2. The brush-holder herein described, comprising, in combination, a holder-body which is closed except at the front end thereof, a follower guided within said body in such manner as to be capable of movement toward and away from said front end of the latter, a notched or toothed stem passing freely through the rear end of said body, a spring-actuated detent-lever pivotally secured to said body and engaging the notches or teeth on said stem, and a spring or springs inter-

posed between said stem and the follower, substantially as set forth.

3. The brush-holder herein described, comprising, in combination, a holder-body adapted to receive at its front end a carbon or other brush, a follower suitably guided within said body and adapted to bear against the rear end of the brush, said follower being provided with a rearwardly-extending wing at each end thereof and with a rearwardly-projecting hub between said ends, a notched or toothed stem passing freely through the rear end of said body, a spring-actuated detent engaging the notches or teeth on said stem, and a coil-spring located within the hub on said follower and engaging the end of said stem, substantially as set forth.

4. In a brush-holder, a holder-body provided with a removable bottom and having its rear end piece connected to or formed integral with said bottom, a follower guided within said body, a notched or toothed stem passing through said rear end piece for advancing the follower within the body, a detent engaging the notches or teeth on said stem for holding the same against rearward movement, and means for locking said removable bottom and rear end piece upon the body, combined and operating substantially as described.

5. In a brush-holder, the combination, with the holder-body having the removable bottom and rear end piece, the follower within said body, the notched or toothed stem passing

through the rear end piece, and the interposed spring, of a detent-lever pivotally connected to said body and having its rear end adapted to engage both said rear end piece and the notches or teeth on said stem and a spring normally holding said lever in such engagement, substantially as described.

6. In a brush-holder, the combination, with the holder-body, the follower guided therein, the notched or toothed stem, interposed spring, and spring-actuated detent engaging said stem, of a stop or stops located at the front end of said body for preventing the escape of the follower therefrom, substantially as described.

7. In a brush-holder, the combination, with the body a , having the removable bottom a' , and rear end piece a^3 , having a rigid connection with said bottom, said end piece having projecting therefrom the hub a^4 , of the follower b , having the rearwardly-projecting hub b^2 , stem d , provided with notches or teeth, as described, and with a suitable head, as d' , said stem passing loosely through said hub a^4 , spring c , secured at its rear end to said stem and having its front end entering the hub on said follower, and a spring-actuated detent on said body engaging the notches or teeth on said stem for preventing rearward movement of the latter, substantially as described.
